UNITED STATES PATENT OFFICE.

CHARLES H. CORNELL, OF VALENTINE, NEBRASKA.

RAILWAY-FASTENING.

No. 921,511.

Specification of Letters Patent.

Patented May 11, 1909.

Application filed May 16, 1908. Serial No. 433,243.

To all whom it may concern:

Be it known that I, CHARLES H. CORNELL, a citizen of the United States, residing at Valentine, in the county of Cherry and State 5 of Nebraska, have invented certain new and useful Improvements in Railway-Fastenings; and I do hereby declare the following to be a full, clear, and exact description of the invention, such as will enable others skilled in 10 the art to which it appertains to make and use the same.

My invention relates to rail fastenings for railway tracks.

It has for its object to provide an improved 15 fastening which is inexpensive and may be quickly adjusted because it does not require the use of screws, spikes or rivets.

Another object is to provide a fastening bolt which may be adjusted to have the 20 proper clamping action and locked at that point even though the proper clamping point on any two bolts should not be the same.

Further objects of the invention will be 25 come apparent from the following description.

It is obvious that the construction of bolt 30 illustrated and described herein as applied to railway rails and ties may also be used for securing parts of other metal construction work such as steel framework for fire proof 35 buildings, steel bridgework, viaducts, etc. While I have herein illustrated and described an I-beam tie in connection with the practice of my invention, it should be understood that 40 other styles of ties may be used. For instance, an ordinary wooden tie may be employed with a metal plate below it to be engaged by the lug on the locking bolt.

The invention contemplates the use of 45 integral bolts provided with laterally extending lugs formed at their lower ends and heads adapted to clamp upon a part to be fastened. The shanks of the bolts with their lugs are passed through key slots with said lugs engaging 50 the under face of the part in which the slots are formed. If said under face is beveled, the turning of the bolts with their lugs riding upon said beveled surface, will give the desired clamping action. Where the lower 55 face of the slotted part is not beveled, I provide the heads of the bolts with spiral cam-shaped under faces which produce the desired clamping effect when said bolts are turned. It will be understood of course, that 60 the spiral cam-shaped heads may be used when the surface of the slotted part engaged

by the lugs is also beveled, the result being that the clamping action is obtained by turning the bolt a much less degree than is required when either the lower face of the 60 slotted part is not beveled or the under faces of the heads are not cam-shaped.

The invention consists further in the features of construction and combinations of parts hereinafter described and specified in 65 the claims.

In the accompanying drawing, illustrating the preferred embodiment of my invention: Figure 1 is a broken side view of an I beam tie to which the rails are fastened by means 70 of bolts made in accordance with my invention, also by means of integral lugs formed on the tie itself. Fig. 2 is a plan view. Fig. 3 is an end view showing a bolt provided with a cam-shaped head. Fig. 4 is an end view 75 showing a bolt not provided with a cam-shaped head. Fig. 5 is a broken side view of a tie and rail fastened together with a modified construction of bolt provided with a series of notches in the edge of its head 80 through which the locking pin is inserted into the extension of the key slot in the tie. Fig. 6 is a plan view thereof. Fig. 7 is a vertical section taken through the key slot. Fig. 8 is a sectional view on the line x—x of Fig. 1, 85 showing the position of the washer which locks the bolt in place. Fig. 9 is a detail view of the washer. Fig. 10 is a broken detail view of the lower end of one of the bolts which has its lug sharpened at the upper 90 edge. Fig. 11 is a broken view looking at the under surface of the flange of the tie through which the lug projects and showing the radial grooves engaged by the sharpened lug, and Figs. 12 and 13 are side and cross 95 sectional views respectively of the ends of two rails with their fish plates fastened together with bolts constructed in accordance with my invention.

Referring particularly to Figs. 1 to 9 inclusive of the drawings, 1 designates an I beam tie of the usual construction having the under faces of its top flange beveled from the web outward. Integral lugs 1^a, extending in the same direction, are preferably 100 formed near the ends of the tie for engaging one side of the foot of each rail thereby reducing by half the number of separable fastenings required. Said upper flange is provided with key slots 2 through which are 105 passed the shanks 3 and radially projecting lugs 4 of the fastening bolts 5. The heads 6

of said bolts are adapted to engage and clamp upon the feet of the rails 7. The under faces of said heads may be spirally cam-shaped as at 8. The edge of the head of each bolt 5 may be serrated as at 9 in Figs. 1, 2 and 3 and said bolts may be locked by having a portion of the washer 10 bent up to engage one of said serrations. Said washer is generally semi-circular in form and has a turned 10 flange 11 at its edge which engages the edge of the foot of the rail and prevents the washer from turning. Part of said turned down flange is cut away as at 12 to permit the shank of the bolt to contact 15 with the foot of the rail. Portions 13 may be cut from either or both ends of the washer for engagement with the serrations in the head. It should be noted that washers of different thicknesses may be used to take up 20 wear and also to provide against the bolt being turned completely around before the proper clamping action is had, which would result in the lug coming up through the key slot.

25 Instead of the serrations, the head of the bolt may be provided with a series of radial notches 14 through one of which the locking pin 15 may be inserted into the extension 16 of the key slot. Because of the repetition of 30 these notches at intervals in the head, one of them will always be in alinement with the extension of the key slots when the bolt is set in clamping position. While I have shown the notched head also provided with a spiral 35 cam-shaped under face, it will be understood that this cam is not required when the under surface of the flange of the tie engaged by the lug on said bolt is beveled.

As shown in Figs. 10 and 11, instead of 40 using the washer described for locking the bolt, the lug on the lower end of said bolt may be sharpened at the top as at 17 and adapted to engage one of a series of radial grooves 18 formed in the under surface of the flange of 45 the tie around the key slot therein. It will be noted that as the bolt is turned and clamped the sharpened edge will be forcibly engaged with one of said grooves and effectually prevent the bolt from becoming loosened.

50 In Figs. 12 and 13, 19 designates the ends of the two rails which are supported by fish plates 20 tapered upwardly as shown in Fig. 13. Key slots 21 are formed through the fish plates and the web of the rails. The bolts 22 55 are preferably passed through said slots alternately from the opposite sides. The lug 23 of each bolt engages one of the fish plates while the head 24 of said bolt engages the other plate. Because of the beveled or 60 inclined faces of the fish plates, the turning of the bolts produces clamping action thereon which forces them tightly against the sides of the webs of the rails. I have shown the heads of the bolts provided with spiral cam-shaped inner faces 24 although this is not ab-

solutely necessary because the riding of the lugs on the beveled surfaces of the fish plates which they engage might give all the clamping action that would be desired. The edges of the heads of the bolts are serrated as at 25 70 and washers 26 are arranged between said heads and the fish plates so that portions thereof may be bent out into engagement with the serrations, for locking the bolts in position. The lower edges of the washers 75 preferably rest upon the base flanges of the fish plates whereby they are prevented from turning.

I claim—

1. A bolt comprising a shank with a laterally extending lug at one end and a head having a spiral cam-shaped under face.

2. A bolt comprising a shank with a laterally extending lug at one end and a head having a spiral cam-shaped under face, the edge 85 of said head having serrations therein for the purpose specified.

3. The combination, with a tie and a rail, of a bolt comprising a shank passed through an opening in the tie, a laterally extending 90 lug on the end of said shank and engaging the under face of the tie and a head on said bolt having a spiral cam-shaped under face engaging and clamping the foot of the rail.

4. The combination, with a tie and a rail, 95 of a bolt comprising a shank passed through an opening in the tie, a laterally extending lug on the end of said shank and engaging the under face of the tie and a head on said bolt having a spiral cam-shaped under face 100 engaging and clamping the foot of the rail, and means to lock said bolt.

5. The combination, with a tie and a rail, of a bolt comprising a shank passed through an opening in the tie, a laterally extending 105 lug on the end of said shank and engaging the under face of the tie and a head on said bolt having a spiral cam-shaped under face engaging and clamping the foot of the rail, the edge of said head being serrated, and a 110 washer having a portion thereof bent up into one of said serrations.

6. The combination, with a tie and a rail, of a bolt comprising a shank passed through an opening in the tie, a laterally extending 115 lug on the end of said shank and engaging the under face of the tie and a head on said bolt having a spiral cam-shaped under face engaging and clamping the foot of the rail, the edge of said head being serrated, and a 120 washer provided with a turned down flange at its edge engaging the edge of the foot of the rail, said washer also having a portion thereof bent-up into one of said serrations.

7. The combination, with a tie and a rail, 125 of a bolt comprising a shank passed through an opening in the tie, a laterally extending lug on the end of said shank and engaging the under face of the tie and a head on said bolt having a spiral cam-shaped under face en- 130

gaging and clamping the foot of the rail, the edge of said head being serrated, and a washer provided with a turned down flange at its edge engaging the edge of the foot of the rail, part of said flange being cut away to permit the shank of said bolt to contact with the foot of the rail, said washer also having a portion thereof bent up into one of said serrations.

10 8. The combination, with a tie having a key slot therein, of a rail, and a bolt comprising a shank with a lug on its end adapted to be passed through said slot and engage the under face of the tie when the bolt is turned, and a head on said bolt adapted to engage and clamp upon the foot of the rail, said lug having its upper edge sharpened and adapted to engage one of a series of radial grooves in the under face of the tie around the slot 20 therein.

9. The combination, with a tie having a key-slot therein, of a rail, and a bolt comprising a shank with a lug on its end adapted to be passed through said slot and engage the under face of the tie when the bolt is turned, and a head on said bolt provided with a spiral cam-shaped under face adapted to engage and clamp upon the foot of the rail, said lug having its upper edge sharpened and 30 adapted to engage one of a series of radial

grooves in the under face of the tie around the slot therein.

10. The combination, with a tie having a beveled under face, of a rail, and a rotatable bolt comprising a shank passed through a 35 passage in said tie and having a laterally extending lug on its lower end engaging the under face of said tie, said bolt also provided with a head engaging the foot of the rail the beveled under face of the tie adapted to act 40 as a cam in connection with the lug on the bolt when the latter is turned whereby the head of said bolt is clamped firmly down upon the foot of the rail.

11. The combination, with a tie having a 45 beveled under face, of a rail, and a bolt comprising a shank passed through a passage in said tie and having a laterally extending lug on its lower end engaging the under face of said tie, said bolt also provided with a head 50 having a spiral cam-shaped under face engaging and clamping upon the foot of the rail.

In testimony whereof, I affix my signature, in presence of two witnesses.

CHARLES H. CORNELL.
